Patented Aug. 18, 1970

218,501

BEDPAN

William J. Gorman, Raytown, Mo., and John G. Markert,
Overland Park, and James S. Reed, Lawrence, Kans.,
assignors to GMR, Inc., Lawrence, Kans., a corpora-
tion of Kansas

Filed May 5, 1969, Ser. No. 17,014

Term of patent 14 years

Int. Cl. D28—01; D24—99

U.S. Cl. D83—1

Fig. 1.

Fig. 2.

Fig. 4.

Fig. 3.

Fig. 5.

FIG. 1 is a top perspective view of the bedpan embodying our ornamental design;

FIG. 2 is a side elevational view thereof;

FIG. 3 is a top plan view thereof;

FIG. 4 is a cross sectional view taken along line 4—4 of FIG. 1; and

FIG. 5 is an exploded top perspective view illustrating the holder and liner components of the bedpan.

We claim:

The ornamental design for a bedpan, as shown.
